UNITED STATES PATENT OFFICE.

JOHN F. CORSER, OF BLOOMSBURG, PENNSYLVANIA.

COMB-CLEANER.

SPECIFICATION forming part of Letters Patent No. 650,371, dated May 29, 1900.

Application filed September 18, 1899. Serial No. 730,898. (No model.)

To all whom it may concern:

Be it known that I, JOHN F. CORSER, a citizen of the United States, residing at Bloomsburg, in the county of Columbia and State of Pennsylvania, have invented a new and useful Comb-Cleaner, of which the following is a specification.

This invention relates to comb-cleaners of that class embodying a plurality of substantially-parallel strands to be passed between the teeth of the comb, and has for one object to provide an improved frame for the support of the strands and for the convenient manipulation of the device.

15 A further object is to provide improved means for adjusting the strands so as to accommodate the device for cleaning combs having teeth of different sizes.

To these ends the present invention consists in the combination and arrangement of parts, as will be hereinafter more fully described, shown in the accompanying drawings, and particularly pointed out in the appended claims, it being understood that 20 changes in the form, proportion, size, and minor details of construction may be made within the scope of the appended claims without departing from the spirit or sacrificing any of the advantages of the invention.

25 In the drawings, Figure 1 is a perspective view of a comb-cleaner constructed in accordance with my invention. Fig. 2 is a longitudinal sectional view thereof. Fig. 3 is a transverse sectional view taken on the line 30 xx of Fig. 2. Figs. 4 and 5 are enlarged detail sectional views taken longitudinally through the respective opposite ends of the device.

35 Corresponding parts in the several figures 40 of the drawings are designated by like characters of reference.

Referring to the accompanying drawings, it will be seen that the frame of the device comprises opposite heads 1 and 2, which are 45 rigidly connected together by means of a handle 3. As clearly shown in the drawings, these heads and the connecting-handle are preferably formed from a single blank of metal having its intermediate portion folded 50 or bent longitudinally into substantially-tubular form to provide the handle, and the opposite ends of the blank are bent at substan-

tially right angles to the handle portion and at the same side thereof, so as to provide the opposite heads. The head 2 is the smaller 55 and substantially circular in shape, while the opposite head 1 is somewhat longer and of triangular form, having the apex thereof located at the end of the handle, so as to provide a comparatively-wide base for the attachment of the strands.

The cleaning-strands 4 are stretched between the two heads, being fixedly connected to the larger head 1 and adjustably connected to the opposite head. These strands are preferably in the form of a wire fabric having no warp-strands, and the opposite ends of the strands are connected together by means of selvage-strips 5, so that the strands may not become separated.

70 As best shown in Fig. 2, the fixed ends of the strands are turned up at substantially right angles to the plane of the strands, and the selvage edge of the same is placed against the inner face of the head 1 and fixed thereto 75 by means of a clamping-plate 6, which extends the entire width of the fabric and is secured in place by suitable fastenings 7, passing entirely through the head, the selvage, and the clamping-plate. The opposite ends of the 80 strands are connected to a substantially L-shaped plate 8, the selvage edge thereof being placed upon the foot of the plate and secured thereto by means of a clamping-plate 9 and fastenings 10, passing through the plate, the 85 selvage, and the foot of the L-shaped plate. This latter plate is located adjacent to the inner face of the head 2 and is adjustably connected thereto by means of an adjusting setscrew 11, which passes loosely through the 90 head and engages a screw-threaded opening 12 in the L-shaped plate. By this construction the plate may be adjusted toward or away from the head 2 by turning the adjusting-screw so as to tighten or loosen the strands. 95

In the operation of the device the handle is held in one hand and the comb in the other, the teeth of the comb being inserted between the strands and then moved quickly back and forth upon the strands, the latter scraping the dirt from between adjacent teeth, and thereby effectively cleaning the comb. To 100 accommodate the device to combs having teeth of different sizes and where the teeth

are farther apart, the adjusting-screw 11 is turned so that the L-shaped plate may be moved or adjusted toward the opposite end of the frame, thereby loosening the strands 5 and permitting of the latter fitting between the teeth. For a finer comb the adjusting-screw is tightened, which draws the L-shaped plate outward, thereby tightening and stretching the strands, which draws the latter closer 10 together for engagement with the more closely disposed teeth of the comb. In some instances it may be found convenient to stand the device upon the head 1 and steady it by means of the handle.

15 Having thus described the invention, what is claimed, and desired to be secured by Letters Patent, is—

1. A comb-cleaner, comprising a frame having opposite heads, a plurality of strands fixedly connected to one of the heads, a substantially L-shaped plate connected to the opposite ends of the strands, and provided

with a screw-threaded opening, and an adjusting-screw carried by the other head and adjustably received within the screw-threaded opening in the L-shaped plate, substantially as and for the purpose set forth. 25

2. A comb-cleaner comprising a frame having opposite heads, a plurality of substantially-parallel strands, selvage-strips embracing the opposite ends of the strands, and connecting the latter together, clamping-plates fitting against the respective selvaged ends of the strands, and holding the latter to the respective heads, and fastenings securing the 30 clamping-plates to the heads, substantially as shown and described.

In testimony that I claim the foregoing as my own I have hereto affixed my signature in the presence of two witnesses.

JOHN F. CORSER.
